LABEL FOR WOUND OR ROLLED FABRICS

Filed March 5, 1928

UNITED STATES PATENT OFFICE.

GEORGE E. BENNETT, OF RIVERSIDE, RHODE ISLAND, ASSIGNOR TO SAYLES FINISHING PLANTS, INC., OF SAYLESVILLE, RHODE ISLAND, A CORPORATION OF RHODE ISLAND.

LABEL FOR WOUND OR ROLLED FABRICS.

Application filed March 5, 1928. Serial No. 259,093.

This invention relates to new and useful improvements in labels, and more particularly to labels for cloth or other fabric wound or supported upon a holder.

5 When cloths and other fabrics are finally prepared for shipment or are to be placed on the market, they are frequently wound upon a holder commonly termed a "board". The board or holder may be of any character 10 or form adapted to support the cloth or fabric, but usually comprises a flat, board-like structure that may be formed of thick stiff paper or cardboard.

It is desirable to provide these bolts or rolls 15 of cloth with tags or labels for indicating the number of yards of material in the roll and such other information as may be needed. Various forms of tags and labels have therefore been provided heretofore for this purpose, but such proposed tags and labels 20 are open to the objection that when they are secured either to the board upon which the fabric is wound or to the fabric itself, they are concealed by the paper wrapper which is 25 commonly placed about the roll or cloth to protect the same, and it has therefore been necessary to provide a second tag or label upon the outside of the paper wrapper and which bears the same information as the tag 30 or label within the package.

Heretofore it has been the practice in many mills to place a small tag or sticker upon the roll of cloth as soon as the same is wound, to indicate the number of yards of cloth in the 35 roll. Later on, when further information is available concerning the roll of cloth, the first tag is removed and a second tag is applied to the cloth indicating the number of yards, goods number, and other data. Then still 40 later a sticker bearing this same information has been applied to the paper wrapper enclosing the roll or bolt of cloth.

The use of these different tags or labels 45 upon the same roll of cloth makes it necessary to copy or transfer the desired data from one tag to another; this involves a loss of time and increases the chances of error occurring in filling out the tags.

Having in mind the foregoing, the present 50 invention relates to improvements in labels whereby the data bearing member may be first attached to the board upon which the fabric is wound and later secured to the pa-

per wrapper enclosing the roll of fabric, thus making it necessary to fill out only one tag 55 or label.

More specifically the present invention relates to a label consisting of a sheet of material such as paper having an anchoring portion adapted to be secured to the cloth board 60 and a data-bearing portion which may be readily torn off from the anchoring portion for application to the outer face of the paper wrapper, and in a relatively long, flexible connection for maintaining a connection between the anchoring portion and data-bearing 65 portion of the label until after the data-bearing portion has been secured to the outer face of the paper wrapper.

The various features of the invention will 70 be best understood from the following description when read in connection with the accompanying drawings, wherein—

Fig. 1 is a face view of a label constructed 75 in accordance with the present invention;

Fig. 2 is a perspective view showing the label of Fig. 1 secured to a cloth board;

Fig. 3 is a longitudinal sectional view 80 through the label and board of Fig. 2;

Fig. 4 is a perspective view showing the 85 board of Fig. 2 with cloth wound thereupon and having the data-bearing portion of the label torn off; and

Fig. 5 is a perspective view showing the 90 data-bearing portion of the label secured to the paper wrapper that encloses the roll of cloth.

In the drawings 10 designates a holder or board of any well known or preferred construction and upon which the cloth or other fabric 11 is wound as usual to form a roll or bolt of fabric ready for the market.

As soon as the fabric 11 is wound upon the board 10 it is desirable to indicate upon the fabric roll the number of yards contained 95 therein. This is accomplished in accordance with the present invention by providing a label formed of paper or other sheet material and having the construction best shown in Fig. 1 and which consists of an anchoring portion 12 and a data-bearing portion 13. One face of the entire label is preferably covered with adhesive and the opposite face of the portion 12 may be provided with the name 100 of the fabric manufacturer or any desired 105 advertising matter. The data-bearing por-

tion 13 preferably has blank spaces where the number of yards in the roll, style and other desired information may be indicated.

The label of Fig. 1 is adhesively secured to the board 10 as shown in Fig. 2 so that the data-bearing portion projects from the end of the board 10, and the label may be secured to the board 10 either before or after the fabric 11 is wound thereon. The number of yards 10 may be easily written upon the projecting portion of the label as shown in Fig. 4. Later on the style, lot number and other desired information may be written upon the projecting portion 13 of the label.

15 When it is desired to wrap the roll of fabric in paper to protect the same the data-bearing portion 13 of the label is torn off from the anchoring portion, and to this end the label is provided with the perforated or otherwise 20 weakened line 14 along which the label forming material may be torn. It is important, however, that the data-bearing portion 13 be prevented from becoming entirely separated from its roll or cloth and lost or confused 25 with the labels for other rolls of cloth. This is prevented, in accordance with the present invention, by providing the label with the relatively long flexible connection 15 which extends through a reenforced eyelet 16 upon the 30 anchoring portion 12 and through a hole 17 formed in the data-bearing portion 13. The flexible connection 15 may comprise a piece of string threaded through the holes 16 and 17 and having its ends tied together as shown.

35 The connection 15 is of sufficient length to extend outwardly through the folded end portion of the paper wrapper 18 as will be apparent from Fig. 5, so that the data-bearing portion 13 remains connected to the anchoring portion 12 until after the roll of cloth is wrapped up and the data-bearing portion is adhesively secured to the outer face of the 40 wrapper where it may be readily observed.

As a result of the present invention all danger of the data-bearing tag 13 becoming separated from the roll of cloth to which it relates is avoided, and the single tag 13 performs the function of the plurality of tags employed heretofore.

45 50 What is claimed is:—

1. A label for cloth wound upon a holder, consisting of a sheet of material comprising a unitary whole having an anchoring portion

adapted to be secured to the holder and a data-bearing portion secured to the anchoring portion by a weakened line along which it may be torn off from the anchoring portion, and a connecting element between said portions in addition to said weakened line to connect the data-bearing portion to the roll of cloth after the data-bearing portion has been torn off from the anchoring portion.

2. A label for cloth wound upon a holder, consisting of a sheet of material comprising a unitary whole having an anchoring portion 55 adapted to be secured to the holder and a data-bearing portion secured to the anchoring portion by a weakened line along which it may be torn off from the anchoring portion, and a flexible connecting element between 60 said portion and of sufficient length to permit the data-bearing portion to be displayed at the outside of a wrapper for the roll of cloth while still connected by said element to the anchoring portion.

3. A label for cloth wound upon a holder, consisting of a sheet of paper comprising a unitary whole having an anchoring portion adapted to be secured to the roll of cloth and a data-bearing portion secured to the anchoring 75 portion by a weakened line along which it may be torn off from the anchoring portion, and a relatively long cord connection between 80 said portions for maintaining a connection between the roll of cloth and data-bearing 85 portion after the data-bearing portion has been torn off from the anchoring portion.

4. A label for cloth wound upon a holder, consisting of a sheet of material comprising an anchoring portion covered with adhesive 90 for attachment to the roll of cloth and a data-bearing portion secured to the anchoring portion by a weakened line along which it may be torn from the anchoring portion and having an adhesive covered face, and a flexible 95 connecting element between said portions in addition to said weakened line and of sufficient length to permit the data-bearing portion to be adhesively secured to the outside of a wrapper for the roll of cloth while still connected by said anchoring portion and flexible 100 element to the roll of cloth.

In testimony whereof, I have signed my name to this specification.

GEORGE E. BENNETT.
